UNITED STATES PATENT OFFICE

2,094,706

ICE REFRIGERATOR

Alma C. Jensen, Salt Lake City, Utah

Application April 27, 1936, Serial No. 76,623

5 Claims. (Cl. 62—37.3)

My invention relates to refrigerators and has for its object to provide a new and highly efficient ice refrigerator which will be able to keep temperatures much lower than those formerly used.

A further object is to provide a refrigerator of the show case type such as are used for meats which is so constructed that the air is drawn from the refrigerating show case compartment down a closed conduit at one end thereof and forced up out through perforated distributing base into and through the ice and up into the refrigerating show compartment along the outside edges thereof thereby accomplishing complete circulation of air, better cooling of the air, and using less power and obtaining greater efficiency from an equal amount of ice.

A still further object is to provide a refrigerator in which meats may be kept a longer period of time with less dehydration and darkening of the meat than has heretofore been possible with other types of ice refrigerators and much longer and more efficiently than possible with mechanical refrigerators.

These objects I accomplish with the device illustrated in the accompanying drawing in which similar numerals and letters of reference indicate like parts throughout the several views and as described in the specification forming a part of this application and pointed out in the appended claims.

In the drawing in which I have shown my refrigerator:

Figure 1 is a vertical longitudinal section of the entire case, parts shown diagrammatically.

Figure 2 is a section on line 2—2 of Figure 1.

Figure 3 is a plan view of one of the tray support shelves.

In the drawing I have shown the outside refrigerator case as A, having the upper portion B provided with glass C in the front face thereof to allow for full vision of the products displayed therein and having sliding doors E on the back of the upper portion. The lower portion F of the casing and the ends are made as usual with suitable outside and inside covering and suitable insulation therebetween for proper construction.

Across the middle of the entire casing dividing the case into two compartments 5 and 6, I provide removable shelves 7 on which the trays are supported. These shelves are made with solid outside frame work 8, angle iron cross braces 9 and 10 across each end, and screen or perforated plate 11 for the rest of the shelf. Thus, air may

pass through the shelves 7 from the compartment 5 into the upper compartment 6.

The trays T are then set down onto the shelves and are made of a size to fit between the angle iron cross braces 9 and 10 leaving the end sections 12 and 13 of the shelves through which air may pass up around the ends of the trays. Also where the trays are set apart, the air may pass up through the portion of the shelves not covered by the trays. The trays T are of the usual butcher tray type used in all display cases. Completely over the bottom of the refrigerator, I then provide a screen floor 15 spaced from the bottom 16 of the refrigerator by suitable spacer bars to allow flushing out of the entire floor of the refrigerator 10 to carry off the accumulated ice slime and deposit left by all ice when melted. Along the center of this I provide an air conduit or duct 18 having openings or ports 19 therethrough and the ice is placed in the case completely covering 20 the conduit 18 and filling the compartment H made for storage of ice.

A partition 21 is provided to divide the lower portion B of the case into ice compartment H and storage compartment K. Near the end of the case 25 I provide an air chamber 17 and leading into this chamber I provide a duct 26 used to blow air from a fan or blower G into this chamber and thence into the conduit 18 and out through the openings or ports 19 into the ice compartment. 30 The suction side of the blower casing is connected with a conduit 22 which extends upwardly through the display portion of the case to the top of the case and is there connected with a longitudinal horizontal conduit 24 leading from one 35 end of the case to the other, drawing off all air from the case through ports 25 into the conduit.

The partition 21 between the ice compartment H and the storage compartment K is provided with an adjustable plate 20 to control the amount 40 of opening over the top of the partition into the storage compartment K. The motor M for driving the fan has a long shaft 28 and the motor is mounted outside the case with the shaft carried through the side wall of the case to the blower 45 thus eliminating all motor heat from the case.

As shown in Figure 2 the angle iron 9 which supports the trays T on the shelves 7 is set farther from the end of the shelves than the brace 10 to allow more air to pass up around the front edge 50 of the shelves than around the rear.

The operation of the case is as follows:

Ice is filled into the ice compartment H and the motor is started. This sucks air from the conduit 22 and the conduit 24 and through the 55

ports from the display compartment B and forces it from the blower G through the conduit 26 into the air chamber 17 and through the conduit 18 out through the ports 19 into the ice. This forced draft forces the air up and around the ice and some of the air strikes directly onto the screens 11 of the shelves 7 passing through to cool the bottom of the trays T and then travels across the bottom of the trays and up around the sides or ends. The rest of the air is forced up through the ice and through the ends 12 and 13 of the shelves and into the compartment B where it is picked up by the suction from the conduit 24 and the cycle of air continued. Part of the forced draft of air is forced over the partition 21 into the store compartment K and then up around the trays which are above this compartment but a complete circulation of air is accomplished with this system.

Having thus described my invention I desire to secure by Letters Patent and claim:

1. In a refrigerator of the display type, the combination of a long display refrigerating compartment; an ice compartment disposed under part of said display compartment; a ported distributing conduit along the bottom of said ice conduit; a perforated collecting compartment disposed along the top of said display compartment; a blower connected with said distributing compartment to blow air through said conduit and through the ice means connecting the collecting conduit with said blower; means to elevate the distributing conduit from the bottom floor of said refrigerator; slanted perforate shelving mounted in said refrigerator in position

to divide the display compartment from the ice compartment, said shelving carrying angle iron braces spaced along the upper side thereof; individual solid bottom trays positioned between said braces on said shelving, said shelving and trays being arranged to allow air forced up through the ice to pass around each tray into said display compartment to refrigerate the food carried on said trays.

2. A structure of the type defined in claim 1 in which said shelving is constructed of separable sections each removable from the refrigerator independently of the other shelves.

3. In a refrigerator of the class described, the combination of a display casing; perforated shelving arranged within said casing to divide the same into two compartments, arranged one above the other; means arranged in the lower compartment to form an ice receptacle therein; a conduit in the lower portion of said receptacle having a closed end and provided with outlets positioned to discharge air through ice in said receptacle; a conduit arranged along the upper wall of the casing and having intake openings distributed along its length; and a blower interposed between and connecting said conduits.

4. The structure defined in claim 3 in which said shelving is provided with spacing means arranged to maintain trays placed on said shelving spaced apart to provide air passage between the same.

5. The structure described and defined in claim 3 in which a motor is mounted outside of said casing and connected to drive said blower.
